DISPLAY PROJECTION CABINET

Donald W. Drilling, Kernersville, N.C., assignor to
Alderman Studios Inc.

Filed July 12, 1972, Ser. No. 270,921

Term of patent 14 years

Int. Cl. D16—02
U.S. Cl. D61—1 N

FIG. 4

FIG. 1 is a front perspective view of a display projection cabinet embodying my new design;

FIG. 2 is a front elevational view thereof, the rear being a mirror image of the front shown;

FIG. 3 is an elevational view taken from one end thereof, the opposite end being a mirror image of the end shown; and

FIG. 4 is an enlarged top plan view thereof.

I claim:

The ornamental design for a display projection cabinet, as shown and described.
